COVER PLATE FOR ELECTRICAL OUTLET RECEPTACLES

Elmer Robert Hayman, Philadelphia, Pa., as
signor of one-half to Herbert Daniel Hayman,
Philadelphia, Pa.

Application May 11, 1949, Serial No. 2,575

Term of patent 14 years

(Cl. D26—13)

To all whom it may concern:

Be it known that I, Elmer Robert Hayman, a citizen of the United States, residing at Philadelphia, in the county of Philadelphia and State of Pennsylvania, have invented a new, original, and ornamental Design for a Cover Plate for Electrical Outlet Receptacles, of which the following is a specification, reference being had to the accompanying drawing, forming part thereof, in which:

Figure 1 is a top or plan view of a cover plate for electrical outlet receptacles embodying my new design;

Fig. 2 is an end elevational view thereof;

Fig. 3 is a vertical section taken on the line 3—3 of Fig. 1; and

Fig. 4 is a transverse section taken on the line 4—4 of Fig. 1.

I claim:

The ornamental design for a cover plate for electrical outlet receptacles, as shown.

ELMER ROBERT HAYMAN.
